US00D342674S

United States Patent [19]

Schollen et al.

[11] Patent Number: Des. 342,674

[45] Date of Patent: ** Dec. 28, 1993

[54] EXPANDABLE CONTAINER**[75] Inventors:** Adrian T. Schollen; John M. Todd,
both of Scarborough, Canada**[73] Assignee:** Expandable Containers ESB Division
of 805004 Ontario Inc., Scarborough,
Canada**[**] Term:** 14 Years**[21] Appl. No.:** 896,560**[22] Filed:** Jun. 10, 1992**[30] Foreign Application Priority Data**Apr. 22, 1992 [CA] Canada 2204923
[52] U.S. Cl. D9/520; D9/301;
D9/528; D9/557**[58] Field of Search** D9/528, 301, 502, 557,
D9/527, 520; 220/666, 669; 215/1 R, 1 C, 100

Primary Examiner—Bernard Ansher*Assistant Examiner*—Lucy Lieberman*Attorney, Agent, or Firm*—Perman & Green**[57] CLAIM**The ornamental design for an expandable container, as
shown and described.**DESCRIPTION**FIG. 1 is a perspective view of the first embodiment of
the expandable container in the fully expanded condition;FIG. 2 is a top plan view of the first embodiment of the
expandable container;FIG. 3 is a bottom plan view of the first embodiment of
the expandable container;

FIG. 4 is a left side elevational view of the first embodiment;

ment of the expandable container in the fully expanded
condition;FIG. 5 is a right side elevational view of the first embodiment
of the expandable container in the fully expanded condition;FIG. 6 is a front elevational view of the first embodiment
of the expandable container in the fully expanded condition;FIG. 7 is a back elevational view of the first embodiment
of the expandable container in the fully expanded condition;FIG. 8 is a perspective view of the second embodiment
of the expandable container in the fully expanded condition;FIG. 9 is a front elevational view of the second embodiment
shown in a fully compressed condition with the
tab on the bottom of the expandable container in an
extended position;

FIG. 10 is a bottom plan view of FIG. 9;

FIG. 11 is a front elevational view of the second embodiment
of the expandable container with the upper
pleated portion in the fully compressed condition and
the lower pleated portion in the fully expanded condition;FIG. 12 is a front elevational view of the second embodiment
of the expandable container with the upper
pleated portion in the partially expanded condition and
the lower pleated portion in the fully expanded condition;FIG. 13 is a front elevational view of the second embodiment
of the expandable container with the upper
pleated portion in the fully expanded condition and the
lower pleated portion in the fully expanded condition;
FIG. 14 is a perspective view of the third embodiment
of the expandable container in the fully expanded condition;FIG. 15 is a top plan view of the third embodiment of
the expandable container;FIG. 16 is a bottom plan view of the third embodiment
of the expandable container;FIG. 17 is a left side elevational view of the third embodiment
of the expandable container in the fully expanded condition;FIG. 18 is a right side elevational view of the third embodiment
of the expandable container in the fully expanded condition;**FIG. 19** is a front elevational view of the third embodiment of the expandable container in the fully expanded condition;

FIG. 20 is a back elevational view of the third embodiment

ment of the expandable container in the fully expanded condition; and,

FIG. 21 is a perspective view of a fourth embodiment of the expandable container shown in a fully expanded condition, the fourth embodiment is the same as the third embodiment except for the number of horizontal pleats.
